IRONING MACHINE

Harold L. Frick, Chicago, Ill., assignor to H. L. F.
Appliance Corporation, Chicago, Ill., a corpora-
tion of Illinois

Application April 23, 1936, Serial No. 75,914

14 Claims. (Cl. 38—26)

My invention relates to ironing machines, and more especially, although not necessarily, to ironing machines of types suitable for domestic use.

Among the objects of my invention are: an ironing machine combining the advantages of both the presser type and the mangle type (I use "mangle" type in its current trade meaning of an ironing machine of the roller-and-shoe type); an ironing machine which may, at the will of the operator, be operated either as a non-feeding presser type or as an automatic feeding type; an improved automatic feed ironing machine; an automatic feed ironing machine which, for its overall dimensions, presents a relatively flat or but slightly crowned working surface, as distinguished from the highly arcuate working surfaces of the usual comparable mangle type; improved mechanism for moving the shoe into and out of contact with the buck, and also an improved combined control for moving the shoe and starting or stopping the feed; an ironing machine automatically feeding the work without accumulating wrinkles in multi-ply work, and in general a simpler, more economical and more rugged construction for ironing machines.

The foregoing together with further objects, features and advantages of my ironing machine are set forth in the following description of a specific embodiment thereof, which is illustrated in the accompanying drawings wherein:

Fig. 1 is a perspective view looking from the right end, showing my ironing machine with its table extended for working position;

Fig. 2 is a more or less diagrammatic transverse section through the table or cabinet for my ironing machine, showing the cabinet portion closed;

Fig. 3 is a transverse vertical section through my ironing machine taken along the line 3—3 of Fig. 1;

Fig. 4 is a longitudinal vertical section taken on the line 4—4 of Fig. 3;

Figs. 5, 6, 7 and 8 are diagrammatic views comparable with the upper right-hand portion of Fig. 3 and showing the buck in four successive positions represented by 90° progressions of the eccentric drive shaft;

Fig. 9 is a plan section of the gear case taken on the line 9—9 of Fig. 3 or Fig. 4;

Fig. 10 is a vertical section of a clutch taken on the line 10—10 of Fig. 9;

Fig. 11 is a vertical transverse section through the gear case taken on the line 11—11 of Fig. 9;

Fig. 12 is a vertical transverse section taken on the line 12—12 of Fig. 9; and

Fig. 13 is a circuit diagram showing, as a modification, a reversible motor and reversing switch therefor.

Referring to Fig. 1, my ironing machine unit indicated generally as 15 is mounted upon a suitable supporting cabinet which may conveniently comprise a table 16, legs 17, a fixed back wall 18 and hinged front and end walls 19 which may be swung out to horizontal position coplanar with the table 16 for the working position of Fig. 1, or which may be folded up into vertical position as indicated in Fig. 2 for enclosing the unit in a cabinet-like structure. A top 20 with downward marginal flanges 20' may be used as a closure for the cabinet with the flanges 20' holding the upturned sides and ends 19 in position for storage as in Fig. 2. In this way the ironing machine may serve as a kitchen table when not in use. The cover 20 may conveniently be stored at the back as shown in Fig. 1 when the cabinet is open for use.

In general my ironing machine unit comprises a base 21 secured to the table 16, a buck 22, a shoe 23, a gear case 24 beneath the table plane 25 for housing the control mechanism, and a driving motor 25.

The buck 22 comprises a frame 26 having thereabove a pad 27 and a fabric covering 28 secured at its margins, as by a drawstring, about 30 the underside of the margin of the plate portion of the frame 26. The buck frame 26 is connected through vertically arranged resilient mounting members 29 with the horizontal arms 30 of floating bearings 31. Somewhat similarly the arms 30 are connected to brackets 32 on the base 21 by vertical resilient mounting members 33, preferably below and in alignment with the respective members 29.

Although I contemplate that the resilient 40 mounting members 29 and 33 may be helical wire springs, for example, I prefer that they take the form of rubber rods. They may conveniently be attached at their ends by screws or studs threaded into short bushings embedded in the rubber at the ends of the rubber rods, as shown in Fig. 3. Preferably there are four sets of resilient mounting members 29—33, one at each end of the arms 30 on the floating bearings 31. The two bearings 31 are preferably beneath the longitudinal median line of the buck 22 and equally spaced from its transverse center, as shown in Fig. 4.

Each floating bearing 31 receives an eccentric end 34 of a buck oscillating shaft 35 which is journaled in a pair of fixed bearings 36 in bridge-like web portions 37 of the base 21.

The shaft 35 carries a pulley 38 driven by a belt 39 from the gear case 24, as will later be described.

As will be seen from Fig. 3, the top surface of the buck 22 is slightly crowned and the underface of the shoe 23 is similarly conformed. The shoe 23 is preferably a casting having electric heating strips 40 in heat conducting contact with the upper side of the shoe casting. The strips 40 are arranged longitudinally of the shoe, one toward the front edge and one toward the back edge. The shoe carries a stamped sheet metal cover plate 41 with the space enclosed by the cover and shoe casting filled with insulating material 42.

For holding the heating strips 40 in firm heat-conducting contact with the shoe 23 I provide a set of four longitudinally spaced retaining clips 44 which extend transversely of the shoe. At its mid-portion each clip is secured to a boss 46 on the shoe by means of a combined cap and socket screw. The opposed ends of each retaining clip bear against the respective heating strips 40. Cap screws 47 threaded into the socket portions of the cap screws 45 in turn hold the cover plate 42 in position.

The shoe 23 is supported by an arm 48 of channel cross section. The shoe is attached to the forward end of the arm 48 by cap screws 49 threaded into suitable bosses in the shoe. The arm 48 extends rearwardly and then downwardly to a fixed pivot 50 on a rearward extension of the base 21. The arm 48 extends downwardly beyond the pivot 50 as an extension 48'. For counter-balancing the weight of the arm 48 and the shoe about the pivot 50 I provide a tension spring 51 horizontally disposed and conveniently housed within a semi-cylindrical hollow rib 52 formed in the base 21. The forward end of the counter-balancing spring 51 is anchored to a hook-like projection or lug 53 extending on the base 21. The rearward end is attached through an adjusted threaded connecting stud 54 to the extension 48' of the arm.

For swinging the arm 48 to move the shoe 14 from its working position of Fig. 3, I employ a pitman 55 extending between a pivot 56 on the arm extension 48' and the offset or crank portion 57 of a shoe-operating shaft 58. In the position illustrated in Fig. 3, the shoe is down and the crank 57 is in dead center relation to the pivot 56 and the shaft 58, and on the arm side of the shaft.

It will be seen that when the shaft 58 is swung, in either direction, through 180 degrees, to bring the crank 57 in dead center relation on the other side of the shaft 58, the arm will be rotated counterclockwise and the shoe thrown to its upper or open position. Conversely, when the shaft 58 is again rotated another 180 degrees to return the crank 57 to the position of Fig. 3, the arm is swung clockwise to bring the shoe to its closed or working position of Fig. 3.

While I contemplate that the shoe-operating shaft 58 may be turned manually to effect the movement of the shoe—in which case the shaft would preferably be mounted farther forward than shown in Fig. 3, for more convenient manipulation—I prefer to operate the shaft by power, but under the control of the operator. For the power operation of the shaft 58 as here shown, I journal the shaft 58 in the respective sides of the previously mentioned gear case 24. A gear 59 is rotatably mounted on the shaft 58 and within the gear case 24. The gear 59 is

driven by a pinion 60 fixed on a power shaft 61 also journaled in the gear case 24 and horizontally disposed parallel with the shaft 58. The power shaft 61 protrudes outwardly of the gear case where it carries a pulley 62 driven through a belt 63 by the previously mentioned electric motor 25.

A sliding clutch member 65 is splined to the shaft 58 and carries steep sided two-way clutch teeth 66 which engage mating teeth 67 on the clutch member 68, which constitutes the hub of the gear 59. A compression spring 69 normally urges the clutch member 65 into engagement with the hub clutch member 68.

Radially beyond the clutch teeth 66 and somewhat backwardly therefrom the sliding clutch member 65 carries a cam face 70 having a pair of diametrically opposed high points 70—a and having a pair of diametrically opposed low points 70—b displaced 90° therefrom. This cam face 70 is adapted to cooperate with the lower end of a square bolt 71, which is mounted, somewhat after the manner of a latch bolt, for vertical reciprocation in bearings 72 extending inwardly from the shell of the gear case 24 (Fig. 11).

Lifting of the bolt 71, which permits re-engagement of the clutch to rotate the shoe-operating shaft 58 through 180°, is provided by a horizontally disposed control shaft 73 arranged at right angles to the shafts 58 and 61, but likewise journaled in the gear case 24. The control shaft 73 protrudes forwardly from the gear case (Fig. 3) and is additionally supported by a bearing bracket 74 depending from the base 21. Forwardly of the bearing 74 the control shaft 73 carries an arm constituting a knee pad 75 which is presented at the left side of the left knee when the operator is seated at the ironing machine.

Referring again to Fig. 11, an outward swinging of the knee pad 75 by the operator's knee turns the control shaft 73 counterclockwise (it being remembered that Fig. 11 is taken on the line 11—11 of Fig. 9 and looking forward). Through a reversing link 76 this imparts a clockwise rotation to a bellcrank 77, which is mounted on a stationary pivot pin 78 on the interior of the gear case.

The bellcrank 77 pivotally carries a trip finger 79 whose protruding end—upon clockwise movement of the bellcrank—engages a shoulder 80 on the cam bolt 71, forcing the latter upwardly until its lower end radially clears the high point 70—a of the cam face 70 of the sliding clutch member 65, whereupon the clutch spring 69 shifts the sliding clutch member 65 to the right, carrying its clutch teeth 66 into engagement with the mating clutch teeth 67 of the hub 68 of the gear 59. The rotating gear 59, being then engaged with the shaft 58, swings its crank 57 through 180° to actuate the shoe, as previously described.

The end of the trip finger 79 will ride off the shoulder 80, leaving the cam bolt 71 free to descend under gravity or a convenient spring. If the operator's knee pressure on the knee pad should be relinquished at any time and the cam bolt 71 should be in the path of the return swing of the trip finger 79, then the trip finger may rock about its pivotal mounting 79' on the bellcrank 77 to foreshorten it temporarily until it can pass to its normal position beneath the shoulder 80. A coil spring 81 (Fig. 3) urges the shaft 73 to its normal position.

As the driven clutch member 65, upon being engaged with the clutch member 68 which con-

stitutes the hub of the gear 59, is rotated through its 180° of movement to swing the shoe, the lower end of the cam bolt 71 rides upon the circumference of the clutch member 65 until it reaches the low point 70—*b* of the cam face of the clutch member 65. There the cam bolt drops down and as the clutch member 65 continues to rotate, the lateral face of the cam bolt 71 rides along the inclined cam face 70 until the high point 70—*a*, diametrically opposite the starting point, is reached. At that point the inclined cam face 70 will have pushed the clutch teeth 66 completely out of engagement with the clutch teeth 69, arresting further rotation of the shaft 58.

For holding the shaft 58 in its diametrically opposed alternate positions corresponding to the up position and the down position of the shoe, I provide a spring-pressed ball detent 82 working in diametrically opposed depressions 83 in the shaft 58.

Having described the operation of the automatic power mechanism for the lifting and lowering of the shoe, I shall now describe the control for the power drive of the buck.

Referring to Fig. 12, which it will be remembered is a view looking forwardly of the ironing machine and taken on the line 12—12 of Fig. 9, further swinging of the knee pad 75 beyond that required for the operation of the clutch control mechanism to swing the shoe to its down position, will impart further counterclockwise (Fig. 12) rotation to the shaft 73. The initial rotation of the shaft 73 will have carried a cross pin 84 through the few degrees of lost motion provided by a diametrical shaft 85 in the hub of a clutch fork 86. The clutch fork 86 engages the ball race ring of a sliding clutch member 87 splined to a sleeve 88 in which in turn is journaled the inner end of the shaft 61 which carries the pinion 60 and which is driven by the outside pulley 62. The conical clutch member 87 cooperates with a friction lined clutch member 89 which is carried by the pinion 60 and secured thereto by the cross pin 90 which passes through the hub of the clutch member 89, through the pinion 60 and through the shaft 61 whereby they rotate as a unit. The sliding clutch member 87 is normally urged out of engagement with its mating clutch member 89 by a clutch spring 91 surrounding the shaft 61 and interposed between the clutch members. After swinging of the knee pad 75 has taken up the lost motion afforded by the slot 85 (Fig. 12), the continued swinging of the knee pad causes the clutch fork 86 to press the sliding clutch member 85 against the pressure of the spring 91 and into engagement with the remaining clutch member 89, whereupon the sleeve 88 is driven by the shaft 61.

The outer end of the sleeve 88 is journaled in a suitable bearing in the gear case 24 and protrudes outwardly of the gear case as a reduced shaft 92 carrying a small pulley 93. The pulley 93, through the previously mentioned belt 39 and pulley 38, drives the oscillating shaft 35 for oscillating the buck.

The oscillation of the buck will presently be discussed. First, to summarize the operation of the control mechanism, suppose that the shoe is in its up or idle position. The operator presses her knee outwardly against the knee pad 75, the initial rocking of the shaft raises the cam bolt 71 to permit engagement of the clutch for the shoe swinging mechanism, whereupon the shaft 58 is rotated through 180° to move the shoe to its

down position. A continued outward movement of the operator's knee in swinging the knee pad 75, after taking up the lost motion in the connection of the shaft 73 with the clutch fork 86, engages the clutch members 87 and 89 to drive the buck oscillating shaft 35 through the belt 39. When the operator releases the knee pad, the return spring 81 rocks the shaft 73 back to normal position, and in doing so permits declutching of the clutch members 87 and 89, stopping oscillation of the shaft 73. To raise the shoe the operator has to push the knee pad slightly again, to operate the cam bolt 71 and initiate another 180° rotation of the shaft 58, which will raise the shoe to its upper position.

If the operator wants to use the machine as a simple flat press iron without the automatic feed feature provided by the oscillation of the buck by means of the shaft 35, then the operator would merely give the knee pad 75 a quick push, sufficient to lift the cam bolt 71, which would result in the shoe being brought down on the buck. Then when the operator wanted the shoe lifted, she would again give the knee pad 75 a quick push to lift the cam bolt 71 a second time, which would result in lifting the shoe.

I shall now discuss in greater detail the nature and function of the oscillation of the buck by the rotation of the shaft 35 by the belt 39.

The eccentric trunnion-like ends 34 of the shaft 35 tend normally to shift the floating bearings 31—and hence the buck 22—through a circular path whose radius is the radius of offset of the ends 34 from the body of the shaft 35. The compressibility and flexibility of the rubber supporting post 33 would permit such a circular path for the buck. However, the buck is so set in relation to the shoe that when work is between the buck and the shoe the actual path of the oscillation of the buck is distorted out of a true circle. In the series of diagrammatic cross sections constituting Figs. 5 to 8, inclusive, I have shown the position assumed by the buck in each of the four successive 90° arcs of a complete rotation of the shaft 35. Starting with the eccentric trunnion-like ends 34 of the shaft 35 in their lowermost positions, which would give the greatest clearance between the buck and shoe, Fig. 5 shows the position of the parts at the end of the first 90° of clockwise rotation of the shaft 35. At that position, depending to a certain extent upon the thickness of the fabric being ironed, the buck will have brought the fabric up into contact with the shoe. During the following 90° of movement of the shaft, which brings the buck to its highest elevation of the cycle, the additional elevation of the floating bearings 31 will cause a compression of the parts between the floating bearings and the shoe. The buck frame being substantially rigid, this compression will take place partly in the resilient pad 27 of the buck, partly in the fabric being ironed and partly in the rubber mountings 29. During the third quarter of the cycle of rotation of the shaft, leading to the position of Fig. 7, the compression will be released and the parts will assume substantially the same position, as regards elevation, as they did in Fig. 5. They will, however, be shifted forwardly, as compared with the position of Fig. 5, by a distance corresponding to twice the radius of eccentricity of the shaft 35. The radius of eccentricity is preferably an eighth of an inch. This gives a lateral (forward and backward from the standpoint of the operator) shift of a fourth of an inch. Since the fabric being ironed is

pressed against the shoe throughout substantially all of the upper half of the circle of movement—that is, from the position of Fig. 5 to the position of Fig. 7—the shoe has a sliding ironing effect upon the fabric for about a fourth of an inch, the pressure of the work against the shoe being at its maximum at the position of Fig. 6. In passing from the position of Fig. 5 to the position of Fig. 7 the work is progressed forwardly about a fourth of an inch. Then in the last 90° of the circle of movement—from the position of Fig. 7 to the position of Fig. 8—the buck is swung sharply downwardly away from the shoe, relieving all pressure between the work and the shoe.

Because the oscillating shaft rotates rapidly, the downward swing from the position of Fig. 7 down through the position of Fig. 8 and back to the position of Fig. 5 is quite sudden relative to the inertia of the fabric being ironed. For this reason the buck is pulled downwardly and shifted back to its rearward position of Fig. 5 much faster than the inertia of the fabric being ironed will permit the fabric to follow. Consequently the fabric remains practically motionless during the back stroke of the buck and is moved by the buck only during the forward or ironing stroke in passing from the position of Fig. 5 to the position of Fig. 7. In this manner the work is progressed through the machine about a fourth of an inch upon rotation of the shaft. The speed of the shaft is preferably such as is calculated, at a fourth of an inch per rotation, to progress the work at about the same speed at which work is progressed through the conventional mangle type ironing machine of comparable capacity.

When the conventional mangle is ironing multiply work, the continuous operation of the roll against the shoe tends to cumulate any relative shifting of the plies and thereby build up sizable wrinkles. This frequently occurs on collars and cuffs. In my ironing machine, when operated automatically to progress the work, I avoid the building up of such wrinkles. While in any given fourth inch of ironing in the course of a single rotation of the shaft there may be a slight relative shifting of the plies, that shifting is not cumulative. This is because the buck is pulled away from the shoe and from the work and is then reengaged with the work and shoe. This virtually intermittent ironing not only does not cumulate any such wrinkling or shifting of the plies, but tends to iron out in the succeeding ironing interval any slight start toward wrinkling which may have developed in the preceding interval.

The resiliency of the four sets of rubber supporting members 29, 33, serves to allow within reasonable limits a universal rocking of the buck relative to the shoe at all times during the cycle. This together with the resiliency of the pad 27 compensates for unequal thicknesses of the work being ironed and for instances where the work is largely in one side or one end of the buck.

At any time when the character of the work being ironed changes from one where an automatic feed is most desirable to one where a simple pressing operation is most desirable, it is a simple matter for the operator, by manipulation of the knee pad, to change over to a simple flat press operation and then back to the automatic feed operation. This may even be done conveniently for different parts of the same garment being ironed as, for example, as between the body, skirt and sleeves of a dress and the collar and trimming. Frequently it becomes desirable

5 to iron with an automatic feed those parts of a garment which are more or less on the straight of the goods, but to use the simple flat press ironing operation on those portions which come on the bias of the goods. My machine makes this feasible and very convenient.

10 On a mangle, or on my machine when operated with the continuous feed, it often happens that as a garment is fed into the iron a button or ornament will be caught by the shoe and be torn off or broken. With my machine it is conveniently possible for the operator, upon seeing such a button or ornament coming to the shoe, to release the knee pad and stop the automatic feed operation and move the work far enough on to the buck to get the button or ornament past the edge of the shoe, perhaps using simple flat pressing for an inch or two, and then continue the automatic feed operation.

15 I have illustrated and described my ironing machine as progressing the work forwardly toward the operator. That is, the work is fed to the rear of the buck and is delivered at the front of the buck. I consider this preferable in most instances because the finished work may conveniently be received into the operator's lap and folded or otherwise disposed of as received, without being confined by the shoe supporting arm 48. It is not so serious if the unironed portion of the work which lies behind the buck is thus confined. However, I contemplate that if it is desired, the work can be fed in the opposite direction, that is, from the front to the rear, as is done with the conventional mangle. This may be done by the 20 simple expedient of making the motor a reversible motor and providing a conveniently located reversing switch, as diagrammed in Fig. 13.

25 For driving out of the pad moisture which would otherwise accumulate therein, I prefer to provide a heating element 94 in the frame of the buck immediately beneath the pad 27. If the work is fed from the back to the front, the heating element 94 would be located toward the rear edge. If the work is fed from the front, then it should be provided toward the front edge of the buck. Where a reversing switch is provided for the motor, whereby the work may be progressed in either direction, I prefer to provide the heating element 94 in both positions, as shown in Fig. 3. 30 In such instance, both heating elements 94 may be operated simultaneously. If desired, however, the electrical connections for the heating elements 94 may be so arranged in connection with the motor reversing switch that when the reversing switch is set to progress the work forwardly the current passes through the rearward heating element 94, and when the switch is set so that the work is progressed rearwardly the current will pass through the forward heating element 94.

35 It will be noted that the control, clutch and operating parts of the power lift for the shoe is so arranged that it permits operation regardless of the direction of rotation of the power shaft 61. 40 This is done to allow for reversing the motor to reverse the direction of feed of the work being ironed.

45 For concealing the operating parts beneath the buck and protecting the operator therefrom, I prefer to provide a peripheral skirt 95 extending upwardly from the base 21 and a skirt 96 depending from the buck and telescoping with the upper end of the skirt 95 in such a manner as to leave room for the forward and backward movement of the buck. In addition, I may add at the front and

also at the back a guard member 97 of sheet metal supported from the base skirt 95 and terminating at the level of the edge of the buck when in its uppermost position. This is indicated only in Fig. 3. It somewhat facilitates the feeding and reception of the work and also aids in holding the work from dropping down when the buck is carried downwardly and rearwardly in the return stroke part of its cycle.

The motor 25, the gear case 24, the bracket 14 for supporting the shaft 13, and the knee pad 75 are all secured to or depend from the underside of the base 21. The buck 22 and the shoe and its arm 48 are mounted on the upper side of the base. Consequently, by removing the anchor bolts which hold the base to the table 16, the entire mechanism may be removed as a unit for repair or replacement, and when thus removed the table with its sides and top 20 may still be used as a kitchen table. The base 21 is anchored to the table 16 through rubber cushioning pads 98, as shown in Fig. 3, so that vibration is not imparted to the table.

I might explain further in reference to the press type of operation of my ironing machine, that the fact that the eccentric carrying shaft may stop at the position where the buck would be down, is of no serious consequence. This is because the effect of the rubber posts is to urge the buck again to its highest position. Since the clutch would be disengaged when the machine was used for simple flat pressing, the rubber posts would push the buck to its upper position. In this way it would be at the right elevation for engagement by the shoe in simple flat pressing.

While I have disclosed these specific embodiments of my invention, I contemplate that many changes and substitutions may be made without departing from the scope and spirit of my invention.

I claim:

1. An ironing machine comprising a shoe member and a buck member having mating surfaces, power driven mechanism tending to oscillate one of the members in a circular path, whose axis is parallel with the mating surfaces of the shoe and buck, and resilient means operatively interposed between the oscillating mechanism and the mating surface of the oscillated member yielding to compression of the oscillated member against the other member for modifying the path of the one member out of the said circular path into a path flattened when the surface of the oscillated member is advanced toward the mating surface of the other member.

2. An ironing machine comprising a buck having a working surface, power driven means for moving the buck in a normally circular path at a radius, in the order of one-eighth of an inch, about an axis longitudinally of and parallel with the working surface of the buck, a heated shoe having a working surface for mating that of the buck, supporting means for moving the shoe from a closed position superposed upon the buck in working relation thereto to an open position exposing the buck for placement of work thereon, and resilient means operatively interposed between the oscillating means and the working surface of the buck and yielding, as the path of the buck approaches the shoe in its closed position, to flatten the normally circular path in the phase where closest to the shoe, for the purpose described.

3. An ironing machine comprising a heated shoe, means for holding the shoe in fixed posi-

tion, a buck positioned therebeneath with a working surface in ironing cooperation with the shoe, a shaft journaled beneath and longitudinally of the buck, an eccentric on the shaft, the buck having a bearing for the eccentric whereby the eccentric tends to shift the buck about a circular path, and resilient means operatively interposed between the bearing and the working surface of the buck and yielding to compression of the buck against the shoe to flatten the circular path.

4. An ironing machine comprising a heated shoe, means for holding the shoe in fixed position, a buck having a padded working surface for ironing cooperation with the shoe, a relatively fixed base, a plurality of resilient supports for the buck extending between the base and buck, each resilient support having an upper and a lower portion, a bearing interposed between the upper and lower portion of the supports, and a driven shaft journaled on the base and having an eccentric position received in the bearing, for the purpose described.

5. An ironing machine comprising a base, a heated shoe pivotally mounted on the base, means for holding the shoe in a fixed working position and for swinging it between the closed position and an open position, a buck having a padded working surface for ironing cooperation with the shoe, a pair of rubber posts disposed on each side of the longitudinal vertical center plane of the buck and interposed between the buck and base for supporting the buck, a shaft journaled on the base and disposed longitudinally of the buck between the pairs of posts, power means for driving the shaft, a manual control for the drive means, and a pair of longitudinally spaced bearings eccentrically mounted on the shaft, the opposite ends of each bearing being interposed between upper and lower portions of posts of the respective pairs.

6. An ironing machine comprising a heated shoe, a base, means for holding the shoe in working position and moving it to and from an upper open position, a buck, means for resiliently supporting the buck from the base and beneath the working position of the shoe for ironing cooperation therewith, a rotary shaft journaled on the base beneath the buck, and an eccentric on the shaft, means connecting the eccentric and buck for shifting the buck back and forth and to and from the shoe intermittently to iron and progress the work.

7. An ironing machine comprising a heated shoe, a base, means for holding the shoe in working position and moving it to and from an upper open position, a buck, means for resiliently supporting the buck from the base and beneath the working position of the shoe for ironing cooperation therewith, a rotary shaft journaled on the base beneath the buck, an eccentric on the shaft, means connecting the eccentric and buck for shifting the buck back and forth and to and from the shoe intermittently to iron and progress the work, and skirts rising from the base and depending from the buck respectively in substantially telescoping relationship for enclosing from the operator the shaft, eccentric and supporting means.

8. An ironing machine comprising a base, means for mounting the base on a table, a shoe disposed forwardly of the base and pivotally mounted on the base rearwardly thereof, a motor suspended from the base below the table, manually controlled means driven by the motor for swinging the shoe from a lower ironing position to an upper open position and including trans-

mission means suspended from the base below the table, a buck resiliently supported from the base beneath the working position of the shoe, a shaft journaled on the base beneath the buck and above the table, manually controlled means for driving the shaft from the motor including transmission means suspended from the base below the table and means beneath the buck and driven by the shaft for shifting the buck laterally of the shoe and to and from the shoe for intermittently ironing and progressing the work.

9. An ironing machine comprising a heated shoe, a base, means for holding the shoe in working position and moving it to and from an upper open position, a buck, means for resiliently supporting the buck from the base and beneath the working position of the shoe for ironing cooperation therewith, a rotary shaft journaled on the base beneath the buck, an eccentric on the shaft, means connecting the eccentric and buck for shifting the buck back and forth and to and from the shoe intermittently to iron and progress the work, and a guard rising from the base and extending outwardly of the buck at the work-receiving edge thereof at a level above the lowest level of the working surface of the buck in its movement to and from the shoe, for aiding in stripping the work from the buck as the buck descends.

10. An ironing machine comprising a shoe, a buck, power driven means for moving the shoe from an open position to a working position in ironing cooperation with the buck, power driven means for shifting the buck against the shoe and alternately relieving pressure and back shifting the shoe, at high frequency intermittently to iron and progress the work across the shoe, and a manually operated lever upon its initial movement initiating operation of the shoe moving means and upon further movement initiating operation of the buck shifting means.

11. An ironing machine comprising a lower buck, a heated upper shoe, means for supporting the shoe for swinging downwardly from an open position into a closed position for simple flat ironing cooperation with the buck, means for supporting the buck for said cooperation and means for optionally holding the shoe in its closed position and gyrating the buck relative thereto in a high frequency cycle which cycle consists in frictional pressure between the buck and shoe accompanied by a forward ironing action to progress the work, followed by relief of the compression at a speed faster than the fall of the

work under gravity without substantial progress or back shifting of the work during the compression relief.

12. An ironing machine comprising a lower buck, a heated upper shoe, means for supporting the shoe for swinging downwardly from an open position into a closed position for simple flat ironing cooperation with the buck, means for supporting the buck for said cooperation, and means, subject to the control of the operator, for optionally holding the shoe in its closed position and gyrating the buck relative thereto in a high frequency cycle which cycle consists in frictional pressure between the buck and shoe accompanied by a forward ironing action to progress the work, followed by relief of the compression at a speed faster than the fall of the work under gravity without substantial progress or back shifting of the work during the compression relief.

13. An ironing machine comprising, a shoe member, a buck member, means for supporting the members in superposed relation for ironing cooperation, and means for moving the lower of the members at high frequency through a cyclic path, which path consists sequentially in movement toward the upper member to compress the work thereagainst, horizontal forward movement while the work is compressed for shifting the work a short distance across the shoe in one direction, downward movement away from the upper member to relieve the compression and, while relieved, horizontal backward movement shifting the lower member in the opposite direction to return it, said downward movement and said back shifting being at such speed as not substantially to back shift the work.

14. An ironing machine comprising a base, a shoe disposed forwardly of the base and pivotally mounted on the base rearwardly thereof, a motor on the base, manually controlled means driven by the motor for swinging the shoe from a lower ironing position to an upper open position and including transmission means supported on the base, a buck resiliently supported from the base beneath the working position of the shoe, a shaft journaled on the base beneath the buck, manually controlled means for driving the shaft from the motor including transmission means supported by the base, and means beneath the buck and driven by the shaft for shifting the buck laterally of the shoe and to and from the shoe for intermittently ironing and progressing the work.

HAROLD L. FRICK.
